UNITED STATES PATENT OFFICE.

GEORGE SMITH BLAKESLEE, OF CHICAGO, ILLINOIS.

DISH-WASHING MACHINE.

1,202,154.

Specification of Letters Patent. Patented Oct. 24, 1916.

Application filed February 15, 1912. Serial No. 677,689.

To all whom it may concern:

Be it known that I, GEORGE SMITH BLAKESLEE, a citizen of the United States, residing at Chicago, in the county of Cook and State 5 of Illinois, have invented certain new and useful Improvements in Dish-Washing Machines, of which the following is a specification, reference being had to the accompanying drawings.

10 My invention relates to dish-washing machines, and has for its object to provide certain improvements in machines of the type shown and described in Letters Patent No. 821,696 and 852,866, both granted to A. W. 15 Bodell, in which one or more paddle-wheels are employed to direct the wash-water against the dishes. I accomplish this object as illustrated in the drawings and as herein-after described. What I regard as new is 20 set forth in the claims.

In the accompanying drawings,—Figure 1 is a longitudinal vertical section of my improved machine on line 1—1 of Fig. 6; Fig. 2 is a plan view thereof; Fig. 3 is a partial 25 side view illustrating the mechanism for rotating the paddle-wheel; Fig. 4 is an enlarged detail, showing the manner of supporting the dish-holding basket while the dishes are being washed; Fig. 5 is a vertical 30 cross-section on line 5—5 of Fig. 1, looking to the right; Fig. 6 is a vertical cross-section on line 6—6 of Fig. 1, looking to the left.

As clearly shown in Figs. 1 and 2, my improved dish-washing machine comprises a 35 dish-washing tank or compartment 7, a rinsing tank or compartment 8 at one side of the washing tank 7, and a compartment 9 at the opposite side of the washing tank, in which is placed the paddle-wheel or equivalent agitating means. The washing tank 7 is separated from the rinsing tank 8 by a partition 10 having an overflow outlet 11 near its upper 40 end so that water from the rinsing tank may be caused to overflow into the washing tank.

45 Both the washing and rinsing tanks are open at the top for the introduction of the basket containing the dishes. The washing tank is not separated from the compartment 9 which contains the paddle-wheel, but 50 guards 12, preferably metal strips or rods, are provided to prevent the basket from striking the paddle-wheel. As clearly shown in Fig. 1, the bottom 13 of the washing tank is at a considerably lower level than the bottom of the compartment 9, the purpose of this arrangement being to provide a

substantially quiet chamber or compartment below the zone where the wash-water is thrown about or agitated in washing the dishes or other articles so that the solid matter liberated by the washing operation may settle in such chamber, thereby, to a certain extent, purifying the wash-water and making it practicable to operate the machine for a longer time without refilling it with fresh water. This settling chamber also serves the purpose of providing a place in which the baskets in which the dishes or other articles are placed may be deposited for a time before they are subjected to the principal 60

washing operation as hereinafter described. 15 indicates the paddle-wheel, which is mounted in the compartment 9 so as to rotate about a transverse axis and thereby direct the water in the compartment 9 forcibly against the dishes in the washing tank. The axis of the paddle-wheel 15 is provided with a pinion 16, as shown in Fig. 3, which meshes with a gear 17 rotated by a crank 18, or other suitable means, such as a motor. As 70 best shown in Fig. 2, the compartment 9 is open only at the side next to the washing tank 7 so that water cannot splash out on to the floor. 19 indicates a tray, which extends over the top of the compartment 9 and serves as a convenient place for filling the basket or depositing dishes to be washed. 20 indicates a similar tray at the opposite 75 end of the machine, adjacent to the rinsing tank 8 for supporting the basket containing the clean dishes or while they are being removed, as illustrated in Fig. 1. 21 indicates a splash board extending across the back of the machine between the trays 19—20. These parts, including the several tanks, are all preferably made of galvanized sheet iron.

22—23—24 indicate legs for supporting the several tanks. 25 indicates a brace for supporting the tray 20. 26 indicates a drain-pipe leading from the rinsing tank 8 and connecting with the main drain-pipe 27. 28 indicates a valve for controlling the flow of water from the drain-pipe 26. 29 indicates a drain pipe connecting the bottom of the washing tank 7 with the main drain-pipe 27, said pipe 29 having a valve 30.

31 indicates an overflow pipe which opens into the washing tank 7 at the depth at which it is desired to maintain the water during washing operations, this opening being best 105 110

located a short distance above the bottom of the compartment 9, as shown at 32 in Fig. 1. The object is to provide sufficient depth of water at the under side of the paddle-wheel 15 to enable it to operate to the best advantage. The pipe 31 connects with the main drain-pipe 27.

33 indicates a steam-pipe which extends into the rinsing tank 8 near the bottom thereof, as shown in Fig. 1, for heating the water in said tank. Instead of using a steam-pipe, any other suitable heating means may be employed, such as a gas burner.

34 indicates a water supply pipe communicating with the rinsing tank 8.

35 indicates a trolley-track, which extends longitudinally of the machine and is substantially over the center thereof, as shown in Figs. 5 and 6, being supported by curved standards 36, as therein shown. The track 35 is for the purpose of supporting a trolley 37 by which the usual dish-holding basket 38 is suspended and shifted from one position to another. As shown in Fig. 1, the basket 38 is provided with a bail 39 which is engaged by a hook 40 at the end of a chain 41 which runs over a pulley 42 suspended from the trolley 37. By this means the basket may readily be moved into its different positions and be lowered into the washing and rinsing tanks or lifted out of such tanks.

In practice the filling basket, resting on the tray 19, is connected with the chain 41 by means of the hook 40 and is then lifted and moved along until it is over the washing tank 7, when it is lowered into said tank until it rests on the bottom thereof, the dishes being then submerged in the water in said tank. At this time the paddle-wheel is not operated. After the dishes have soaked long enough, the basket is raised until it occupies an intermediate position in the washing tank, and the paddle-wheel is driven rapidly, thereby forcing the wash-water violently against and through the dishes. This is continued until the dishes are thoroughly cleansed.

By extending the bottom of the washing tank a considerable distance below the bottom of the compartment 9, a settling chamber or compartment is provided in which the solid matter washed from the soiled dishes is deposited and where it remains practically undisturbed notwithstanding the agitation of the water in the upper portion of the tank, since while the paddle-wheel 15 is in operation the water supplied to it comes from a zone above the settling chamber and not from the settling chamber itself, the water in which is prevented from flowing under the paddle-wheel by the construction shown, and consequently is not agitated to any great extent.

In order to support the basket in its in-

termidiate or washing position, the pulley 42 is provided with a depending hook 43, which is adapted to engage a link 44 of the chain 41 placed in suitable position so that when said hook engages such link the basket 70 will be held suspended at the proper height. The engagement of the hook 43 with the link 44 is shown in Fig. 4.

After the dishes have been thoroughly cleansed, the basket is hoisted out of the 75 washing tank and deposited in the rinsing tank, which is full of very hot water, and after being rinsed are withdrawn and the basket is deposited on the tray 20.

It will be seen that by the construction 80 described I provide a very compact apparatus in which the several operations of washing the dishes may be expeditiously and efficiently carried on. Moreover, my improved machine is simple in construction 85 and therefore the cost of manufacture is not only reduced but there is very little mechanism to get out of order, and consequently the cost of maintenance is very low.

While my improved machine is intended 90 primarily for washing dishes, it may be used for any other purpose to which it is adapted, and the claims are therefore to be construed accordingly.

That which I claim as my invention, and 95 desire to secure by Letters Patent, is,—

1. A washing-machine, comprising a wash-water holding-tank, a compartment at one side thereof and communicating laterally therewith, and means in said compartment for throwing wash-water against the articles to be washed, said tank extending below the level of the bottom of the compartment containing said water-throwing means to provide a settling chamber below 105 the washing zone in which solid matter may accumulate.

2. A washing-machine, comprising a wash-water holding-tank, a compartment at one side thereof and communicating laterally therewith, means in said compartment for throwing wash-water against the articles to be washed, said tank extending below the level of the bottom of the compartment containing said water-throwing means to provide a settling chamber below the washing zone in which solid matter may accumulate, and means for supporting the articles to be washed in said tank above said settling chamber.

3. A washing-machine, comprising a wash-water holding-tank, a compartment at one side thereof and communicating laterally therewith, a paddle-wheel in said compartment and operating by its rotation to discharge water into the upper portion only of said tank, said tank being extended below the zone of operation of said paddle-wheel to provide a settling chamber in which solid matter may accumulate.

4. A washing-machine, comprising a wash-water holding-tank, a compartment at one side thereof and communicating laterally therewith, a paddle-wheel in said compartment and operating by its rotation to discharge water into the upper portion only of said tank, said tank being extended below the zone of operation of said paddle-wheel to provide a settling chamber in which solid matter may accumulate, and means for supporting the articles to be washed in a position opposite said paddle-wheel.

5. A dish-washing machine, comprising a washing tank open at the top, a compartment opening into said washing tank at one side, the bottom of said compartment being at a higher level than the bottom of the washing tank, and a paddle-wheel in said compartment arranged to rotate about a horizontal axis disposed transversely of the machine.

6. A dish-washing machine, comprising a

washing tank open at the top, a compartment at one side of said washing tank and opening thereinto, the bottom of said washing tank extending below the bottom of said compartment, means in said compartment for throwing the wash water against the dishes to be washed, and an overflow outlet leading from said washing tank at a point above the bottom of said compartment.

7. A dish-washing machine, comprising a washing tank open at the top, a compartment at one side of said washing tank and opening thereinto, the bottom of said washing tank extending below the bottom of said compartment, means in said compartment for throwing the wash water against the dishes to be washed, and a tray arranged over said compartment.
